US0D1067765S

(12) **United States Design Patent** (10) **Patent No.:** **US D1,067,765 S**
(45) **Date of Patent:** **** Mar. 25, 2025**

(54) **MOUNT**

(71) Applicant: **Zeal Innovation Ltd.**, Swansea (GB)

(72) Inventor: **Neil Anthony Barron**, Swansea (GB)

(73) Assignee: **Zeal Innovation Ltd.**, Swansea (GB)

(**) Term: **15 Years**

(21) Appl. No.: **29/873,331**

(22) Filed: **Mar. 29, 2023**

(30) **Foreign Application Priority Data**

Sep. 29, 2022 (GB) 6235314

(51) **LOC (15) Cl.** **08-05**

(52) **U.S. Cl.**

USPC **D8/354**
